HARRY A. INMAN, OF NEWARK, NEW YORK

RECEPTACLE

Application filed October 1, 1928. Serial No. 309,603.

This invention relates to a receptacle of the type made by folding a blank of sheet material so as to form a liquid-tight container such, for example, as an oyster pail. The principal object of the invention is to provide a more simple and practical receptacle of this nature which is more nearly liquid-tight than similar receptacles heretofore known.

Another object of the invention is the provision of improved and more nearly liquid-tight closure means for closing the top of the receptacle to prevent escape of liquid therefrom.

A further object is the provision, in a receptacle of the type having corner folds, of means for sealing these folds to prevent escape of liquid from the receptacle through the corner folds, in conjunction with improved liquid-tight closure means for the receptacle.

To these and other ends the invention resides in certain improvements and combinations of parts, all as will be hereinafter more fully described, the novel features being pointed out in the claims at the end of the specification.

In the drawings:

Fig. 1 is a perspective view of a receptacle constructed in accordance with a preferred embodiment of the invention, illustrating the closure flaps in open position;

Fig. 2 is a similar perspective view illustrating part of the flaps in closed position and one of the flaps in open position;

Fig. 3 is a plan of a blank which may be folded up to form the receptacle; and

Fig. 4 is a vertical section taken approximately centrally through the receptacle, with the closure flaps in closed position.

Similar reference numerals throughout the several views indicate the same parts.

There is shown in Fig. 3 a blank so shaped that it may be folded up to form a receptacle such as is illustrated in Figs. 1, 2 and 4. This blank has a portion 10 forming the bottom of

the receptacle, and portions 11 forming the front wall, 12 forming the rear wall, 13 forming one side wall, and 14 forming another side wall. When the portions 11, 12, 13 and 14 are folded up at an angle to the bottom 50, the corner portions 15 are folded along

the lines 16, and these corner folds may be laid against the front and rear walls 11 and 12, as shown in Figs. 2 and 4.

It has been found in practice that there is usually some leakage out of a receptacle of this kind through the corner folds. When a liquid or semi-liquid is carried in the receptacle, it works its way around the corners of the receptacle into the space between the adjacent layers 15 of the corner folds, and then seeps out through the tops of these corner folds as the receptacle is jarred or shaken while it is being carried.

To prevent such leakage, the present invention contemplates the provision of an adhesive connection between the adjacent layers 15 of the corner folds. The adhesive, which may be any suitable cement or glue, is shown at 17 in Fig. 3. When the blank is folded up to the shape shown in Figs. 1 and 2, this strip of adhesive will unite the two layers forming each corner fold with each other along their top edges, and thus will effectively prevent leakage from the receptacle through the corner folds.

The blank shown in Fig. 3 may be provided with portions arranged to form closure flaps, which may be folded down across the top of the receptacle to close it when desired. For instance, there may be a flap 20 connected to the upper edge of the front wall 11 of the receptacle, this flap being of the shape shown in Figs. 1 and 3. This flap preferably is of such size and shape that it covers the entire area of the top of the receptacle when it is folded down to its effective position extending across the top, and preferably it has a secondary flap 21 attached to the edge opposite to that which is connected to the front wall 11. When the main flap 20 is in effective position, this secondary flap 21 may be folded down into the receptacle, as shown in Fig. 4.

Flaps 22 and 23 connected to the upper edges of the side walls 13 and 14, respectively, are arranged so that they may be folded down on top of the flap 20 when the latter is in effective position across the top of the receptacle, and a flap 24 secured to the edge of the rear wall 12 may be folded down across

the flaps 22 and 23. This flap 24 may be provided with a suitable fastening member, such as a metallic tongue 25 arranged to be inserted through an opening 26 in one of the corner folds 15, the tongue being bent back upon itself as shown in Fig. 4 to hold the flap 24 in closed position. This flap 24 serves to maintain the other flaps below it in closed position.

10 In previous receptacles of this general type, there has ordinarily been more or less leakage along the edges of the closure members. One of the principal causes of such leakage has been the fact that the pressure of the contents of the receptacle caused the sides to bulge outwardly and thus to become slightly separated from the edges of the closure members, leaving a space through which the contents might leak. Heretofore, no provision has been made for reducing or preventing the leakage caused by this bulging of the sides. The present invention provides closure flaps especially adapted to overcome this defect, and to form a cover 15 which substantially eliminates or materially cuts down the amount of leakage from the top of the receptacle, notwithstanding the bulging of the sides.

From Figs. 1 and 3 it will be noted that 20 the two sides edges 30 and 31 of the flap 20 are not straight, but are slightly curved. The amount by which these edges deviate from a straight line is preferably made slightly greater than the amount of deviation 25 caused along the tops of the side walls 13 and 14 by pressure of the contents of the receptacle. Thus this flap 20 fits tightly against the side walls 13 and 14 when it is in its effective position, even when these walls 30 are bulged outwardly. Preferably the length 35 of the flap 20, from the edge connected to the wall 11 to the opposite edge of the flap, is made slightly greater than the distance across the top of the receptacle from the front wall 40 11 to the rear wall 12.

Thus the flap 20, when forced down into place, fits tightly against the walls of the receptacle around all sides, and acts as a satisfactory closure, especially when used in 45 conjunction with the other flaps 22, 23 and 24 above mentioned. The secondary flap 21 lies against the wall 12 of the receptacle, the natural resiliency of the material tending to straighten it out and thus keeping its lower edge pressed against the wall 12 to form a 50 tight joint. The curved edges 30 and 31 of the flap 20 form tight joints with the sides 13 and 14 of the receptacle, the edges of the flap 20 being held in place by the side flaps 22 and 23, which aid in maintaining a liquid-tight joint along the edges. The top flap 24 holds the other flaps in place, and also aids in providing a tight joint along the rear edge of the receptacle. Thus it is seen that 55 a particularly effective closure is provided,

which is substantially liquid-tight in ordinary use, and is much superior to the closures heretofore provided on receptacles of this character.

Any suitable handle may be provided for the receptacle, such as the bail 35 having its ends hooked through the corner folds 15.

While one embodiment of the invention has been disclosed, it is to be understood that the inventive idea may be carried out in a number of ways. This application is therefore not to be limited to the precise details shown, but is intended to cover all variations and modifications thereof falling within the spirit of the invention or the scope of the appended claims.

I claim as my invention:

1. A receptacle including a body portion having a substantially rectangular open top and closure members therefor folded from a single blank of sheet material, said closure members including a flap integrally connected to said body portion along one edge of said open top and of proper dimensions to extend across and cover the entire area of said open top, and a plurality of flaps connected to other edges of said open top and arranged to be folded down on top of said first named flap, and fastening means for holding the uppermost flap in closed position, said first named flap having edges convexly curved to compensate for outward bulging of the sides of said receptacle and to insure liquid-tight engagement therewith.

2. A receptacle including a body portion having a substantially rectangular open top and closure members therefor folded from a single blank of sheet material, said closure members including a flap integrally connected to said body portion along one edge of the open top and of proper dimensions to extend across and cover the entire area of said open top, said flap having edges convexly curved to compensate for outward bulging of the sides of said receptacle and to insure liquid-tight engagement therewith, said flap also having a secondary flap connected thereto along the edge opposite to that connected to the body portion and arranged to extend downwardly from said flap and to lie in contact with a side wall of said receptacle to provide a liquid-tight joint between said flap and said wall, flaps connected to the edges of said open top adjacent the edge to which the first named flap is connected and arranged to be folded down on said first named flap, and a flap connected to the edge of said open top opposite to the edge to which said first named flap is connected and arranged to be folded down on top of said first named flap and said second named flaps, and fastening mechanism for holding said last named flap in said folded down position.

3. A receptacle including a body portion

having a substantially rectangular open top and closure members therefor folded from a single blank of sheet material, said receptacle having corner folds each comprising two surfaces of substantially triangular outline integrally joined together along one edge and lying in superposed relation, an adhesive connection between said two surfaces of each corner fold to seal each corner fold for preventing escape of liquid from the receptacle through the corner folds, said closure members including a flap integrally connected to said body portion along one edge of said open top and of proper dimensions to extend across and cover the entire area of said open top, and a plurality of flaps connected to other edges of said open top and arranged to be folded down on top of said first named flap, and fastening means for holding the uppermost flap in closed position.

4. A receptacle including a body portion having a substantially rectangular open top and closure members therefor folded from a single blank of sheet material, said receptacle having corner folds each comprising two surfaces of substantially triangular outline integrally joined together along one edge and lying in superposed relation, an adhesive connection between said two surfaces of each corner fold to seal each corner fold for preventing escape of liquid from the receptacle through the corner folds, said closure members including a flap integrally connected to said body portion along one edge of the open top and of proper dimensions to extend across and cover the entire area of said open top, said flap having edges convexly curved to compensate for outward bulging of the sides of said receptacle and to insure liquid-tight engagement therewith, said flap also having a secondary flap connected thereto along the edge opposite to that connected to the body portion and arranged to extend downwardly from said flap and to lie in contact with a side wall of said receptacle to provide a liquid-tight joint between said flap and said wall, flaps connected to the edges of said open top adjacent the edge to which the first named flap is connected and arranged to be folded down on said first named flap, and a flap connected to the edge of said open top opposite to the edge to which said first named flap is connected and arranged to be folded down on top of said first named flap and said second named flaps, and fastening mechanism for holding said last named flap in said folded down position.

HARRY A. INMAN.
